UNITED STATES PATENT OFFICE.

GEORGE W. CALKINS AND JOHN WOODHILL, OF CLEVELAND, OHIO; SAID WOODHILL ASSIGNOR TO SAID CALKINS.

ELEVATOR-BUCKET.

SPECIFICATION forming part of Letters Patent No. 256,100, dated April 4, 1882.

Application filed October 8, 1879.

To all whom it may concern:

Be it known that we, GEORGE W. CALKINS and JOHN WOODHILL, of Cleveland, in the county of Cuyahoga, State of Ohio, have invented certain new and useful Improvements in Hoisting-Buckets, which are fully described in the following specification and the accompanying drawings, in which—

Figure 1 represents a derrick having one of our improved buckets suspended thereto. Fig. 2 is a vertical section of the bucket. Fig. 3 is a plan of the bottom of the bucket.

Our invention relates to buckets used in handling and dumping coal, stone, and other articles—as, for example, in loading and unloading vessels; and the invention consists of a peculiarly-pivoted bucket and of its operating devices, as hereinafter fully described.

A designates the body of the bucket, made usually of iron.

B is an angle-iron hoop, secured to the bottom edge of the bucket. The bottom D of the bucket is made preferably of wood, because it is lighter, cheaper, and lasts longer than iron, and in order that the lower end of the bucket may not be too heavy. This wooden bottom rests on two iron cross-bars, C C, which are supported by the hoop B, as shown.

The bucket is pivoted within and to the bail E by means of the projecting pins F, fixed to the body A at such points as that the center of gravity of the empty bucket will be below the pivots and the center of gravity of the loaded bucket will be above the same pivots.

G is a metallic piece fastened at the top to the outside of the bucket, and provided with a central notch, and tapered from the notch toward each end, forming a catch for the spring-latch H, adjusted in a slot or recess, I, in one arm of the bail. The spring-latch is provided at its upper end with an eye for attaching to it a cord, J, for releasing the bucket from the latch, which is adjusted to bear against the catch G and automatically spring into its notch when the bucket returns to the upright position. The upper part of the bail is adapted to be suspended to any derrick or crane for hoisting and conveying the bucket to the places for charging and discharging it.

It will be observed that the automatic dumping of the bucket and its return to an upright

position depend upon and are secured by the vertical adjustment of the pivots above and below the centers of gravity of the empty and loaded bucket, as described, and that therefore the pivots may be located on the vertical center line of the bucket, thus allowing the use of an entirely round bucket, which is cheaper and more readily made than the usual form of an oblong or angular bucket, and also allowing the bucket to be dumped and emptied as readily at one side as at the other, thus facilitating the accurate discharge of its contents at the precise place required; and a bucket thus constructed, adjusted, and pivoted will automatically assume and maintain, while empty, an upright position without the use of stops or other appliances ordinarily employed in hoisting-buckets.

These features of construction and adjustment we consider essential to the rapid and accurate manipulation of the bucket in charging as well as discharging it.

The empty bucket, being in the upright position shown in Fig. 1 of the drawings, where it is securely held by the spring-latch, is filled and conveyed to the place of deposit, when the spring-latch H is drawn out of the notch of the catch G by the rope J, and the center of gravity being above the pivots, the bucket automatically dumps and empties itself, and when emptied, the center of gravity being below the pivots, the bucket automatically returns to the upright position, the latch automatically springing into the notch of the catch G and fastening the bucket in the position for reloading.

It will be readily seen that the point of location, vertically, of the pivots depends somewhat upon the comparative weight of the lower and upper ends of the bucket. That precise point is ascertained by any suitable devices after the bucket is made, it being essential to the easy, rapid, and proper operation of the bucket that the pivots be located so that when the bucket is empty there will be just enough of preponderance of weight below the pivots to carry the bucket to the upright position with sufficient force only to move backward the latch and allow it to spring into the notch of the catch G.

It is evident that if the pivots should be

placed too low the bucket would not automatically return to the upright position, and if the pivots should be placed too high, the empty bucket would return with too great force, and 5 the loaded bucket would not so readily, if at all, dump and completely empty itself.

What we claim as new, and desire to secure by Letters Patent, is—

1. A hoisting-bucket suspended upon pivots 10 located so as to be above the center of gravity of the empty bucket and below the center of gravity of the loaded bucket, whereby the loaded bucket, when released from its latching devices, will automatically dump and empty it- 15 self at either side, and when emptied the bucket will automatically return to and latch itself in

an upright position, substantially as and for the purposes described.

2. The combination of a pivoted bucket having a notched catch with a bail provided with 20 a recess or slot, and having a spring-latch arranged in the recess or slot, the devices and combination operating in the manner described, whereby rapid charging and discharging of the bucket is accomplished, substantially as set 25 forth.

G. W. CALKINS.
JOHN WOODHILL.
